UNITED STATES PATENT OFFICE

2,457,292

SMOKE AND SOOT ELIMINATOR

Roger F. Williams, Des Moines, Iowa

Application February 27, 1946, Serial No. 650,654

2 Claims. (Cl. 183—110)

1

The principal object of my invention is to provide a device for eliminating excess smoke and soot extruding from furnaces and like combustion chambers.

A further object of this invention is to provide an excessive smoke control that is of simple construction and easily installed.

A still further object of this invention is to provide a smoke and soot control that salvages the soot and other combustible matter for useful purposes.

A still further object of my invention is to provide a device for eliminating undesirable smoke and soot from furnaces and like that is economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a side view of my device with sections cut away to more fully illustrate its interior construction.

Fig. 2 is a cross-sectional view of the device taken on line 2—2 of Fig. 1.

The damage caused by excessive smoke in cities and industrial areas is one of the problems of modern times. Local smoke abatement regulations have proven ineffective and elaborate and complicated smoke reduction equipment is impossible for the average installation. Due to the simplicity of my device it is particularly adapted for store, factory, hotel, and like use.

In the drawings I have used the numeral 10 to designate a conventional combustion chamber in which coal, wood, or like is burned. The numeral 11 designates the usual smoke and hot gases outlet pipe. It is to such an installation that I attach my smoke and soot control device. 12 designates an elongated horizontal housing having a plurality of spaced apart vertical baffle walls 13 rising from its inside bottom and terminating some distance from its inside top, as shown in the drawings. The numeral 14 designates a compartment having a downwardly and rearwardly extending bottom and communicating with the outside bottom of the housing 12. The numeral 15 designates an opening in the bottom of the housing forward of each of the baffle walls 13 and communicating with the inside of the compartment 14. 16 designates a pipe communicating with the pipe 11 and the rear end of the

2

housing 12. The numeral 17 designates a fan and fan housing communicating with the pipe 16. 18 designates an electric motor operatively connected to the fan. 19 designates a pipe having one end communicating with the forward end of the housing 12 at a plane below the upper edges of the walls 13 and its other end communicating with a chimney 20. The numeral 21 designates a downwardly extending outlet pipe communicating with the inside bottom of the compartment 14 capable of being closed by a gate or like valve 22. The numeral 23 designates a pipe having one end communicating with the inside bottom of the compartment 14 and the inside 10 of the combustion chamber 10. This pipe is capable of being closed or opened by the gate or like valve 24. The baffle walls 13 may be of impervious construction but in one of them I show openings 25, as shown in Fig. 2, to encourage uneven flowing of the hot gases through the device. The baffle walls 13 may be unevenly spaced apart to increase vortex within the housing and I preferably space them closer together as they progress forwardly within the housing.

25 The practical operation of my device is as follows: The hot gases from the combustion chamber laden with smoke and soot particles pass into the rear end of the housing 12 and swirl over and downwardly of each of the baffle walls 13 as the same progress forwardly through the housing 12 and to the chimney 20. This uneven flow of the gases will cause a dead space forward of the lower portions of each of the baffle walls and the soot and like smoke particles will drift into and collect forward of each of the baffle walls. This collection of particles will by gravity fall through the openings 15 provided in the bottom of the housing and into the compartment 14. By the time the gases reach the forward end of the housing the soot and smoke particles will have been substantially separated from the gases and collected within the compartment 14 from which they will pass into the pipes 21 and 23. If desired, the gate 24 may be closed, the gate 22 30 opened, and this collected matter salvaged for useful industrial purposes. It has been found that most soot and smoke particles are combustible for soot and smoke particles are caused by improper combustion within the combustion chamber. If desired, the gate 22 may be closed and the gate 24 opened, thereby permitting this combustible material to return to the combustion chamber for consumption, thereby making the furnace or like more efficient. In most installations

tions the fan 17 will not be necessary as a chimney 20 will provide sufficient draft.

Some changes may be made in the construction and arrangement of my improved smoke and soot eliminator without departing from the real spirit and purpose of my invention, and it is my intention to cover by my claims any modified forms of structure or use of mechanical equivalents which may be reasonably included within their scope.

I claim:

1. In a device of the class described, a housing, a plurality of spaced apart vertical baffle walls inside said housing each extending from the bottom of said housing and terminating a distance from the top of said housing to provide a straight uninterrupted flow of gases above them, soot outlet openings in the bottom of said housing, a conduit communicating with the inside of said housing at a point below the top planes of said baffle walls and its other end communicating with the inside of a combustion chamber, an outlet pipe having one end communicating with the outside atmosphere and its other end communicating with the inside of said housing at a point below the top planes of said baffle walls, a collecting compartment on the bottom of said housing communicating with said openings and having its bottom sloping toward and communicating with the inside of said combustion chamber, a means for closing the inside of said collecting compartment from said combustion chamber at times, an outlet conduit communicating with the inside bottom of said collecting compartment, and a means for closing said last-mentioned conduit at times.

2. In a device of the class described, a housing, a plurality of spaced apart vertical baffle walls inside said housing each extending from the bottom of said housing and terminating a distance from the top of said housing to provide a straight uninterrupted flow of gases above them, soot outlet openings in the bottom of said housing, a conduit communicating with the inside of said

housing at a point below the top planes of said baffle walls and its other end communicating with the inside of a combustion chamber, an outlet pipe having one end communicating with the outside atmosphere and its other end communicating with the inside of said housing at a point below the top planes of said baffle walls, a collecting compartment on the bottom of said housing communicating with said openings and having its bottom sloping toward and communicating with the inside of said combustion chamber, a means for closing the inside of said collecting compartment from said combustion chamber at times, an outlet conduit communicating with the inside bottom of said collecting compartment, a means for closing said last-mentioned conduit at times, a power means communicating with the inside of said first-mentioned conduit for inducing the movement of gasses through the same and into said housing, and passageways in at least one of said baffle walls.
